UNITED STATES PATENT OFFICE.

JOSEPH ELON ROSE, OF PORTLAND, OREGON.

DENTAL CROWN STRUCTURE.

1,425,055.

Specification of Letters Patent. Patented Aug. 8, 1922.

Application filed March 13, 1918. Serial No. 222,052.

To all whom it may concern:

Be it known that I, JOSEPH ELON ROSE, a citizen of the United States, residing at Portland, county of Multnomah, State of Oregon, have invented certain new and useful Improvements in Dental Crown Structures, of which the following is a specification.

The present invention relates to dental crown structures. One object of the invention is to provide a structure of this class which shall be suitable for a tooth whether serving as an individually crowned tooth by itself or as an abutment for a dental bridge. Another object of the invention is to provide a crown structure in which the crown comprises a jacket having the exterior configuration and color of a natural tooth.

In carrying out the invention the enveloping jacket is preferably composed of porcelain and a base of gold is interposed between it and the prepared natural tooth, the parts being held together by a suitable adhesive, such as dental cement. The base may be in the form of a ring which engages the upper portion of the interior wall of the jacket, or in the form of a shell which engages practically all portions of the interior wall of the jacket. The latter, of course, provides the more rigid structure and is preferable for bridge work.

The invention will be more fully understood upon reference to the following description taken in connection with the accompanying drawings, and the scope of the invention will be particularly pointed out in the appended claims.

Referring to the drawing, Fig. 1 is a front elevation of a dental bridge structure, having abutments constructed according to the present invention; Fig. 2 is a rear elevation of the same; Fig. 3 is a perspective view of a portion of said bridge structure, showing the abutment crown in central vertical section; Fig. 4 is a view of an individual crown shown in vertical section in position on a prepared tooth, said view illustrating the gold base in the form of a shell, and Fig. 5 is a similar view illustrating the gold base in the form of a band or ring. Throughout these views like reference characters refer to like parts.

Referring to said drawing in detail, A and B designate the abutment crowns of the bridge structure C. The latter structure includes a bridge 10 of gold and a plurality

of teeth 11 suitably secured thereto. At each end, the bridge 10 is formed integral with or suitably secured to the base of gold forming part of the abutment crown. Since the 60 crowns A and B are alike, it will suffice to describe the structure of crown A only. This structure includes the jacket 12 of porcelain or like material and the base 13 of gold which is preferably in the form of a shell 65 which fits against all portions of the inner wall of the jacket 12. The jacket is given an exterior shape which conforms to that of the natural tooth which it is intended to replace. It is also composed of a material, preferably porcelain, which has a color closely approaching that of a natural tooth. The gold base 13 preferably extends slightly beyond the open end of the jacket 12 and its exposed exterior portion is made 70 flush with the adjacent portion of the jacket so that its exterior surface forms an extension of the exterior surface of the jacket 12. This exposed portion of the base 13 preferably forms a band or ring which 75 finishes off the open end of the jacket. The base 13 may be secured to the jacket 12 by an interposed adhesive, such as dental cement.

In practice many jackets can be made up 80 and kept on hand. These will vary in size and shape according to the different shapes and sizes of natural teeth.

When it is desired to make a crown, the natural tooth, such as the tooth designated 90 14, is prepared by removing the enamel, then a suitably selected jacket 12 is fitted over the prepared tooth, with two sheets of gold foil, separated by a layer of wax, intervening. The foil and wax when fitted 95 and trimmed will take the shape of the finished base 13. Then the jacket together with the foil and wax are carefully removed from the tooth 14, and finally the foil and wax is removed from the jacket 12, care being 100 taken not to change its shape. The wax and foil form is then invested in a suitable material such as plaster of Paris, with a small portion of the wax exposed. The wax is then burned out and the gold is flowed 105 in to take its place. When removed from the investing material and properly finished this constitutes gold base 13, which is to be fitted into jacket 12 and cemented into place by the use of dental cement or other adhesive. 110 With the final polish the crown is now ready for application to the prepared

tooth. This is done by merely applying an adhesive to the interior of the base and fitting the whole upon the tooth 14, where it will be held by an adhesive. Of course, in 5 the case of the bridge construction, both abutment crowns should be set at the same time.

In case the base is a ring instead of a shell, it is formed in the same way but the 10 foil and the wax are cut away before investing so as to leave a gold base like 13' of Figure 5. In such case the gold base is not interposed between the end portion of the tooth 14 and the jacket 12 but the latter 15 bears directly upon that portion of the tooth with the adhesive intervening.

It will be understood that the jackets can be produced by a manufacturer while the work upon the base is done by the dentist. 20 Other ways may be employed for preparing the base of gold and more or less of the base may be allowed to show when the crown is completed. These and other modifications of the structure and the method of putting 25 it into place may be made without departing from the spirit and scope of my invention.

What I claim as new and desire to secure by Letters Patent of the United States is:

1. A dental crown structure comprising an 30 enveloping jacket having the exterior configuration and color of a natural tooth and open at one end so as to be readily slipped over a prepared tooth, and a base of gold having its exterior surface secured to the 35 interior of said jacket and having its interior surface adapted to be secured to the exterior of the prepared tooth by an adhesive.

2. A dental crown structure comprising an enveloping jacket having the exterior configuration and color of a natural tooth and 40 open at one end so as to be readily slipped over a prepared tooth, and a base of gold fitted into the interior of said jacket at its open end and having an exterior surface

forming an extension of the exterior surface 45 of the adjacent portion of said jacket.

3. A dental crown structure comprising an enveloping jacket having the exterior configuration and color of a natural tooth and open at one end so as to be readily slipped over a 50 prepared tooth, and a base of gold constituting a shell fitted into the interior of said jacket and firmly secured thereto, said shell having a portion extending beyond the open end of said jacket, said portion having exterior faces flush with and extending the faces of the adjacent portions of said jacket.

4. A dental structure comprising a bridge of gold, teeth secured thereto, an abutment base of gold to which said bridge is secured, 60 said base being shaped to fit upon and be secured to a prepared tooth, and an enclosing jacket fitting upon and secured to a portion of said base and having the exterior configuration and color of a natural tooth. 65

5. A jacket crown for teeth of porcelain having a cavity of a size to receive the prepared crown of the natural tooth and having at the open end of the cavity a surface encircling the cavity and approximately perpendicular to the axis of the cavity and adapted to abut a shoulder formed between the natural tooth crown and the root, and having within the cavity a matrix of metal having a marginal flange fitting the said end 70 surface of the porcelain jacket crown. 75

6. A jacket crown having a cavity of a size to receive the prepared crown of a natural tooth, and having the said cavity lined with a matrix of metal. 80

7. A tooth crown comprising a jacket crown having a cavity to receive a natural crown and a lining matrix formed to fit said cavity.

In testimony whereof I have hereunto subscribed my name this 15th day of February, A. D. 1918.

JOSEPH ELON ROSE.
